ATTORNEYS.

UNITED STATES PATENT OFFICE.

DANIEL A. ANDREWS, OF CEDAR KEYS, FLORIDA.

DESIGN FOR A BRUSH.

61,358.

Specification for Design. Patented Aug. 15, 1922.

Application filed April 15, 1922. Serial No. 1,773. Term of patent 7 years.

To all whom it may concern:

Be it known that I, DANIEL A. ANDREWS, a citizen of the United States, residing in the city of Cedar Keys, county of Levy, and State of Florida, have invented a new, original, and ornamental Design for a Brush, of which the following is a specification, reference being had to the accompanying drawing, forming a part thereof.

In the drawings Fig. 1 is a front elevation of the brush, and Fig. 2 is a side elevation thereof, showing my new design.

I claim:

The ornamental design for a brush, as shown.

DANIEL A. ANDREWS.
